(57) **CLAIM**

The ornamental design for a cutting and serving board, as shown and described.

DESCRIPTION

FIG. 1 is a perspective view of an open configuration of the cutting and serving board, showing my new design; FIG. 2 is a front elevation view of the cutting and serving board in the open configuration; FIG. 3 is a rear elevation view of the cutting and serving board in the open configuration; FIG. 4 is a top view of the cutting and serving board in the open configuration; FIG. 5 is a bottom view of the cutting and serving board in the open configuration; FIG. 6 is a right elevation view of the cutting and serving board in the open configuration; FIG. 7 is a left elevation view of the cutting and serving board in the open configuration; and, FIG. 8 is a perspective view of a closed configuration of the cutting and serving board.

The broken lines shown in the drawings depict portions of the cutting and serving board that form no part of the claimed invention.
